UNITED STATES PATENT OFFICE.

JOHN F. DALY, OF PHILO, ILLINOIS.

GRAIN-BOARD FOR WAGONS.

SPECIFICATION forming part of Letters Patent No. 372,522, dated November 1, 1887.

Application filed August 1, 1887. Serial No. 215,871. (No model.)

To all whom it may concern:

Be it known that I, JOHN F. DALY, of Philo, in the county of Champaign and State of Illinois, have invented certain new and useful 5 Improvements in Throw-Boards and Grain-Aprons for Wagon-Beds; and I do hereby declare the following to be a full, clear, and exact description of the invention, such as will enable others skilled in the art to which it pertains to make and use it, reference being had to the accompanying drawings, which form part of this specification.

My invention relates to an improvement in throw-boards and grain-aprons for wagon-beds; 15 and it consists in the combination, with the wagon-bed, of two metallic supports which straddle down over the side of the bed, the throw-board, which is hinged to these supports, the rods which support the board in an upright 20 position while in use, and a supporting rod or brace, which supports the board when it is inclined outward from the bed, as will be more fully described hereinafter.

The object of my invention is to provide a 25 throw-board and grain-apron for wagon-beds, and which is adapted to be used upon both sides of the wagon alike, and which not only serves as a stop for the ears of corn as they are being thrown into the wagon by the huskers, 30 but as side-boards for catching the thrashed grain while it is being hauled from the thrashing-machine to the granary, and a rack upon which to haul hay.

Figure 1 is a vertical section of a device embodying my invention, taken through one of the 35 hinges. Fig. 2 is a side elevation of the wagon-bed, showing the board inclined outward.

A represents an ordinary wagon-bed, and 40 B the two metallic supports which straddle down over the opposite edges of one of the sides of the bed and to which the throw-board C is pivoted. These metallic supports B extend any suitable distance down over the top 45 edge of the bed, and have a suitable thickness at their top to allow a pivotal bolt, D, to be passed through. Secured to the inner side of the throw-board C are the metallic braces or plates E, which are recessed at their lower ends, 50 so as to catch over the upper ends of the supports B, and to have the pivotal bolt pass

through them. These plates or braces E are recessed in such a manner that when the board C is raised into a vertical position they act as stops to prevent the boards from being inclined 55 inward over the top of the wagon-bed. The board C being loosely pivoted to the supports by means of the plates or braces, the board can be freely turned outward, so as to stand at an angle to the wagon-bed, as shown, and thus 60 form a rack upon which hay can be piled, and so that the board will be out of the way in unloading the bed.

Loosely connected to the outer side of the board C is a supporting-rod, G, which passes 65 down through a guiding-loop, H, which prevents the rod from swinging freely outward, and thus holds it always in position, so that its lower end will strike against the side of the wagon-bed, and thus support the board at a 70 suitable angle. In order to prevent the bed from becoming injured by the lower end of the brace-rod bearing against it, a metallic rub-plate, I, is secured to the side of the bed, as shown. This brace-rod prevents the throw-board from 75 being turned outward beyond a suitable angle while the bed is either being used for hauling hay or when the wagon-bed is being emptied of its contents. When the board is being used as a throw-board, it is held in a vertical position by 80 means of the two rods J, which are loosely connected to the inner side of the board, and which catch in eyes L, attached to the opposite inner side of the wagon-bed.

In husking corn it is necessary that a throw-board should be attached to one side of the wagon-bed in order to prevent the ears of corn which have been husked from being thrown over the opposite side of the wagon-bed by the husker. This throw-board is nearly always used upon the right side of the bed, but as here constructed is equally as well adapted to be used upon either side alone, or a board upon each side, as may be desired. In hauling hay a board will be placed upon each side, 90 and they will be inclined outward, as shown, so as to form racks upon which to pile the hay. In unloading the corn the throw-board will also be inclined backward, so as to be out of the way, and at the same time prevent a portion of the corn from falling over the side of the bed upon the ground. In hauling grain 95 100

from the thrashing-machine to the granary two of the boards will be used, and these boards form grain-aprons which prevent the grain from being spilled upon the ground.

5 Having thus described my invention, I claim—

1. The combination of the wagon-bed, with the metallic supports which straddle down over the top edge of one side of the bed, the throw-board, and the metallic plates or braces rigidly secured thereto, and by means of which the board is pivoted to the supports, and the brace-rods by which the board is held in a vertical position, substantially as shown.

2. The combination of the wagon-bed, the supports, the grain-board which is pivoted to the supports, the brace-rod which is loosely connected to the outer side of the board, and the loop which keeps the brace-rod in position, substantially as described.

In testimony whereof I affix my signature in presence of two witnesses.

JOHN F. DALY.
